UNITED STATES PATENT OFFICE.

ARTHUR DOAN, OF ELMHURST, CALIFORNIA.

AIR-BRAKE SYSTEM.

973,179.

Specification of Letters Patent. Patented Oct. 18, 1910.

Application filed November 18, 1909. Serial No. 528,645.

To all whom it may concern:

Be it known that I, ARTHUR DOAN, citizen of the United States, residing at Elmhurst, in the county of Alameda and State of California,

5 have invented new and useful Improvements in Air-Brake Systems, of which the following is a specification.

This invention relates to air-brake systems, and pertains particularly to automatic 10 safety appliances for use in railway brake systems.

The objects of my invention are to provide an automatic brake applying apparatus of extreme simplicity; to provide in conjunction 15 with the usual manually controlled air-brake system a safety device perfectly automatic in operation; to provide a safety attachment inexpensive in construction which may be readily connected to any 20 standard air-brake system; and also to provide an appliance whose action is directly controlled by the pressure of the brake-operating fluid in the train line.

The invention consists of the parts and 25 the construction and combination of parts as hereinafter more fully described and claimed, having reference to the accompanying drawings, in which the figure is a dia- 30 grammatic plan of the appliance, with the safety device in section.

A is the train-line which carries the air or other fluid under pressure from the cab on the engine back through the train of cars, the flow of air through the train-line being 35 suitably controlled to actuate the brakes.

While my invention is susceptible of a variety of constructions and arrangements, I have shown in the present instance a high pressure air reservoir or reserve high pressure tank 2, suitably supported on a car and connected by a pipe 3, in which is a check-valve 4, to the train-line A. From the train-line A fluid under pressure may pass the check valve 4 and enter the reservoir 2, so 45 as normally to maintain in reservoir 2 a reserve of fluid under maximum train-line pressure. In the event, however, of a reduction of pressure in the train-line A the valve 4 prevents the fluid in the high pressure reservoir 2 from escaping back through pipe 3 to the train-line A, and when needed the extra pressure in reservoir 2 is available for operating the brakes in the manner about to be described.

50 55 6 is a brake cylinder connected by means

of the pipe sections 7—7' to the usual triple valve 8 which is controlled by the engineer through the instrumentality of the fluid in the train-line A.

The operating fluid is allowed to pass 60 from train-line A through a pipe 9 and the triple valve 8 in the usual manner into a brake-reservoir or auxiliary 10, from which it may pass through the triple valve 8 and connections 7—7' to effect the operations of 65 a brake-piston in the cylinder 6. Frequently, however, the rapid, successive applications of the brakes on a train, as when descending a grade, or traversing crossings or switches, cause the pressure of fluid in 70 the train-line and brake reservoir to become so greatly diminished that sufficient force cannot be exerted upon the brakes to check the speed of the train, and unless the pressure is quickly built up by the compressor a 75 runaway train is the inevitable result.

Sometimes when a train is climbing steep 80 grades the couplings part, in which case one section of the train is entirely disconnected from any means for rebuilding the pressure 85 in the train-line A, with consequent serious wrecks and fatalities. Therefore, for the purpose of avoiding such a failure of the brakes and to insure their positive application at such critical occasions, I provide a 90 relatively small, simple device interposed between the high pressure tank 2 and the brake cylinder 6, whereby on the decrease of pressure in the train line below a point sufficient to operate the brakes effectively, the extra 95 pressure in tank 2 will be available. As shown, a valve cylinder 11 is connected at its upper end by a suitable pipe 12, with the reservoir 2; and the lower enlarged portion 13 of the cylinder is directly in communica- 100 tion with the train line A through the pipe 14.

Within the upper smaller chamber of the cylinder 11 is slidable a suitable piston valve 15 provided with a transverse port 16 105 adapted, with the piston in one position, normally to be in register with the pipes 7—7', which are tapped into the cylinder 11, thus permitting a free flow of fluid from the brake reservoir 10 to the brake cylinder 6. 110 Moving piston valve 15 in the opposite direction uncovers a port 20 to bring the high pressure reservoir 2 into communication with the brake cylinder 6. The lower end of the piston 15 is reduced or provided with 115

a stem 17, which passes through a stop plate or partition 18 in the cylinder 11.

Suitably secured to the stem 17 is a piston 19 in the enlargement 13 of the cylinder; 5 this piston 19 being considerably greater in area than the piston valve 15, which difference of areas results in the ported piston valve 15 being maintained in such position, by pressure from the train-line A and pipe 10 14, that the piston 19 is forced upward against the stop 18 and the port 16 registers with the pipes 7—7', so that ordinarily with a normally effective pressure in the train line the brakes are operated from the train 15 line through the triple valve and the high pressure reservoir 2 is cut off from the brake cylinder.

If for any cause whatsoever pressure is abnormally reduced in the train-line A, the 20 reserve pressure of fluid in the high pressure reservoir 2 will act immediately upon the upper end of piston valve 15, forcing it to traverse the cylinder 11 and by so doing will uncover port 20 by which communication 25 will be established, through duct 21 in the side of cylinder 11, with the brake-cylinder 6 and by this means a pressure equal to that 30 of the normal maximum train-line A is exerted to apply the brakes, and this irrespective 35 of the pressure or lack of pressure in the train line and brake reservoir 10 after the piston 15 once passes the opening or port 20. The stop plate 18 limits the travel of the piston 15, and when pressure is again 40 built up to normal or maximum in the train line A it will act upon the head 19 to return the piston 15 to allow of the normal action of the triple-valve 8 and reservoir 10 through port 16. Simultaneously with the 45 increase of pressure in the train-line A the charge in the reservoir 2 will be replenished and the pressure built up in readiness to be effective again the instant an abnormal reduction of pressure against the head 19 occurs. Therefore, it will be noticed that I 50 have provided a device of simple construction in which there is but one movable element and one main casting, to wit, the cylinder 11. No fine adjustments are required and the device is entirely automatic.

Having thus described my invention, what I claim as new and desire to secure by Letters-Patent, is:—

1. The combination in an air brake system, of a train-line, a brake cylinder, a high pressure reservoir connected with the train-line and also having a fluid connection with the brake cylinder, a valve cylinder in the connection between the brake cylinder and 55 the high pressure reservoir, a piston valve in said valve cylinder, one end of said piston valve subject constantly to the pressure in the high pressure reservoir, means by which a difference in pressure between the high 60 pressure reservoir and train-line results in

the movement of said piston valve to admit fluid from the high pressure reservoir to the brake cylinder, and a triple valve having fluid connections with the train-line and with the brake cylinder, said connections 70 between the triple valve and brake cylinder being controlled by said piston valve.

2. The combination in an air brake system, of a train-line, a brake cylinder, auxiliary reservoir, triple valve, connections between the train-line through the triple valve and auxiliary reservoir to the brake-cylinder, a by-pass connection between the train-line and brake cylinder around the triple valve, a high pressure reservoir in said by-pass connection and chargeable from the train line, and a piston valve interposable in said by-pass and in the connections between the train-line and triple valve, said piston valve permitting flow from the train-line 85 through the triple valve to the brake cylinder simultaneously cutting off communication through the by-pass between the high pressure reservoir and brake-cylinder, and means for operating the piston valve by the 90 differential action of the train-line and high pressure cylinder pressures.

3. The combination in an air brake system, of a train-line, a brake cylinder, a high pressure reservoir connected with the train-line and also having a connection with the brake cylinder, another connection between the train line and brake cylinder, and a valve common to said last named connection and to the connection between the high pressure reservoir and brake cylinder by which one of said connections will be open when the other is closed, and vice versa, and means by which said valve is operated through the differential action of pressures 100 in the train-line and high pressure reservoir.

4. In an air brake system, the combination of a train-line, a brake cylinder, a high pressure reservoir connected with the train line, a valve cylinder, a differential piston 110 in the cylinder, a connection between one end of the cylinder and the train line, and a connection between the other end of the cylinder and the high pressure reservoir, said valve being operable by the differential action of the pressures in the train line and high pressure reservoir, a connection between the brake cylinder and the end of the valve cylinder which is connected with the high pressure reservoir, said connection between the brake cylinder and valve cylinder being normally closed by said valve and a connection between the train line and brake cylinder.

5. An automatic air-brake system comprising, in combination, a train-line, a brake-cylinder, a brake-reservoir, a connection between said cylinder and reservoir, a high pressure reservoir connected with said train-line, and means directly interposed in

the connection between the brake-cylinder and the brake reservoir through which communication may be established between the high pressure reservoir and the brake cylinder, said means including a piston operable by the difference in pressure in the train-line and in the high pressure reservoir.

In testimony whereof I have hereunto set my hand in the presence of two subscribing witnesses.

ARTHUR DOAN.
